Primary Examiner—Melanie Tung*Assistant Examiner*—Susan Moon Lee(74) Attorney, Agent, or Firm—Trexler, Bushnell, Giangiorgi, Blackstone & Marr, Ltd.(57) CLAIM

I claim the ornamental design for a watering disc for poultry, as shown and described.

DESCRIPTION

FIG. 1 is a perspective view of the watering disc for poultry according to my design;

FIG. 2 is a top view thereof;

FIG. 3 is a bottom view thereof; and,

FIG. 4 is a left side view of the watering disc for poultry, the right side being identical.

1 Claim, 3 Drawing SheetsFIG. 1

FIG. 4
